[57] CLAIM

The ornamental design for a rear portion of a top surface for a videotrack cassette, as shown and described.

DESCRIPTION

FIG. 1 is a perspective view of a rear portion of a top surface for a videotrack cassette showing our new design; and,

FIG. 2 is a top plan view thereof.

The broken line showing of the videotrack cassette and tape reel is for illustrative purposes only and forms no part of the claimed design.
